METHOD AND APPARATUS FOR MAKING
SCREWS AND THE LIKEJohn H. Friedman, Tiffin, Ohio, assignor to The
National Machinery Company, Tiffin, Ohio, a
corporation of Ohio

Application April 27, 1945, Serial No. 590,556

17 Claims. (Cl. 10—26)

1

My invention relates to headers, and particularly header tools for forming recessed heads.

Header tools for punching recesses into the heads of articles, and for similar duties, are frequently subjected to lateral bending stresses which tend to break the hardened tool steel or other material from which the tools are formed. Any non-uniformity in the distribution or physical properties of the material being punched tends to deflect the point of the tool away from its true axial direction after it has entered the material. Inaccuracies in the shape of the tool, and play of the header slide in its bearings have similar tendencies. The tool must be rigidly supported by the header slide in order that the point will enter the material to be punched, so that in the usual constructions any deflection of the tool after it has entered the material applies a bending force to the relatively brittle tool.

The principal object of this invention is to eliminate the breaking of header tools from this cause. Other objects are to rigidly support and center a tool at the time it first engages the work piece and to free the tool for slight lateral movements during the remainder of the working stroke after the tool has become guided by the work piece; to relieve possible inaccuracy of previous heading operations; and to relieve or allow for lack of symmetry in tools, in blanks, or in the composition of the material of which the blank is composed.

Other and further objects, features and advantages of the invention will become apparent as the description proceeds.

A better understanding of the invention will be afforded by the following detailed description considered in conjunction with the accompanying drawing and the scope of the invention will be set forth in the claims.

In the drawings:

Fig. 1 is a longitudinal sectional view of a schematically indicated apparatus representing the action of the first blow of a double-blow header for forming a screw with a recessed head;

Fig. 2 is a longitudinal sectional view of the apparatus employed in the second blow of a double-blow header in accordance with an embodiment of my invention showing the initial step in piercing the head of the blank;

Fig. 3 is a view corresponding to Fig. 2 representing a more advanced step in the process;

Fig. 4 is a view corresponding to Figs. 2 and 3 showing the relative positions of parts upon the completion of the recess in the head of the blank; and

2

Fig. 5 is a perspective view of a blank with the recessed head completed.

Like reference characters are used throughout the drawing to designate like parts.

In carrying out my invention in its preferred form for producing recessed screw heads, I utilize a conventional double-blow header. Different tools are utilized in the first and second blows of the header. In the first blow a blank non-recessed head is formed in the conventional manner. In the second blow the head is pierced with a suitable tool producing, for example, the four-winged socket or recess characteristic of Phillips screws. A conventional type of piercing tool may be employed. However, the tool is provided with a special mounting which initially centers the tool with respect to the blank head, but allows the tool to drift laterally after a predetermined relative longitudinal motion has taken place between the die carrying the blank head and the piercing tool. To this end a tapered or frusto-conical wedge may be employed initially urged outward to rigidly center the tool, which is loosened to permit lateral motion of the tool as the header and die come together.

Referring to Fig. 1 of the drawing, for the first blow of the header a blank 11 is held within a suitable die 12, mounted in a bed frame (not shown) and a conventional heading tool 13 is provided for forming a blank head 14 on the end of the wire stock 11. The die 12 is provided with the usual knockout rod 16, which may also serve to back up the blank during the heading blow.

For carrying out the second and final operation on head 14 of the blank 11, a piercing tool 17 is provided as illustrated in Figs. 2, 3 and 4. As in conventional double-blow headers, a tool carrier 18 is mounted upon a reciprocating header slide, and carries in different positions the header tool 13 and a suitable mounting for the final header tool or piercing tool 17. In the arrangement illustrated, the tool carrier 18 has a portion 19 adapted to have the piercing tool 17 mounted therein. The tool carrier may be mounted upon the header slide and operated in the manner disclosed in my prior Patent No. 1,955,061, April 17, 1934, and the patent to Clouse No. 1,932,396, October 31, 1933, to which patents reference is made for a disclosure of a machine upon which the present invention may be used. It is, of course, to be understood that the present invention may also be used upon other double-blow headers.

For supporting the tool 17 a mounting is provided comprising a chuck or wedge 21 supported within a socket member 22 having a tapering in-

ner opening. A cylindrical cavity 23 may be provided in the portion 19 of the tool carrier 18 to receive the mounting members 21 and 22. The chuck 21 has a substantially cylindrical bore 24 within which the tool 17 is adapted to fit loosely to permit relative longitudinal motion of the tool 17 and the chuck 21. The tool 17 is so arranged that its backward motion or motion toward the bottom of the socket or cavity in the tool carrier 18 is limited. An anvil 25 is provided for this purpose. Preferably means are provided for limiting outward motion of the tool 17 with a little lost motion and for causing the extraction of the piercer 33 to begin before the chuck 21 has moved out far enough on the extraction stroke to restore realignment. To accomplish this, annular grooves 26a and 26b are formed in the anvil 25 and the tool 17, respectively, and a longitudinal split thimble 26c is provided, which engages the grooves 26a and 26b to limit the separation between the anvil 25 and the tool 17 to the amount represented by the space 26d in Fig. 1. The chuck 21 has an increased diameter around the thimble 26c with a shoulder 26 sufficiently near the outer end of the chuck to permit the chuck 25 to recede the required distance into the socket member 22.

The chuck 21 has an outer surface tapering to a smaller diameter toward the end, and the socket member 22 has an inner surface 28 tapering to a smaller diameter at the open end of the socket. The surfaces 27 and 28 are adapted to fit one another and if desired, the surfaces may form portions of a conical surface to produce frusto-conical members.

Suitable means are provided for securing the socket member 22 in the cavity 23. For example, a set screw 29 may be provided. Means are provided for normally holding the chuck 21 outward with its outer surface 27 wedged tightly against the inner surface 28 of the socket member 22 for the purpose of centering the tool 17 initially. For this purpose, resilient means such as a compression spring 31 may be employed.

The working edges of the piercing tool 17 may be of conventional configuration. For example, as illustrated the tool 17 is provided with a piercing tip 33 having four wings or fins 34, such as to produce a four-winged slot or recess in a screw head. The tip 33 is formed in a portion of a spherical socket 35 at the end of a substantially cylindrical bar or shank forming the tool 17.

In forming recessed screw blanks from wire or rod stock, a suitable blank is first cut off in the cut-off station of the apparatus (not shown) and thereafter the blank 11 is transferred to the die 12. The tool carrier 18 is moved to such a position that the header tool 13 comes opposite the die 12 whereupon the numbers 12 and 13 are driven toward each other so as to form the head 14. It will be understood that the blank 11 is at the time located by the knockout rod 16.

Thereafter the tool carrier 18 is moved to such a position that the mounting members 21 and 22 and the piercing tool 17 are brought opposite the die 12. Then power is applied for bringing the header slide 18 and the die 12 together. Initially the spring 31 holds the chuck 21 outward with its frusto-conical surface 27 tight against the frusto-conical inner surface 28 of the socket member, 50 to center the piercing tip 33 of the header tool 17 rigidly and accurately with respect to the die 12 and the head 14 of the blank 11. The first action which takes place after the space 26d has been closed, is that the piercing tip 33 enters the

head 14 approximately at the center thereof, the exactness of the center depending upon the accuracy of alignment of the tool parts, the wear thereof, and the accuracy with which the head 14 5 was formed by the header tool 13. Further relative motion between the header slide 18 and the die 12 causes the vanes 34 of piercing tip 33 to sink more deeply into the head 14. However, there may be a tendency for the piercing tool to drift bodily if there is any inaccuracy in the initial centering or in the mounting of the parts, or if there is any lack of uniformity of the hardness of the metal in the blank 11, or other lack of concentricity. To prevent such tendency for drifting from applying a bending force to the tool, the chuck 21 is so mounted that it may be freed laterally to a limited extent as it is moved in longitudinally.

After the tip 34 has sunk into the head 14 sufficiently to start and guide the tool, the outer surface or end 36 of the chuck 21 comes into engagement with the surface 37 of the die 12, whereby the chuck 21 is caused to be moved inward relative to the socket member 22 against the force of the compression spring 31. This action is illustrated by the position of the parts in Fig. 3 with the part of the die 12 at its surface 37 in engagement with the end portion or part 36 of the chuck 21. As further motion takes place, the tool sinks more deeply into the head 14. The chuck 21, having moved inward, is freed from tight engagement with the inner socket surface 28 so as to permit limited lateral movement thereof, thus allowing the tool to drift slightly in one direction or the other.

The tool 17 is supported within the chuck 21 which, in turn, is prevented from leaving the cavity 23 by reason of the tapering confronting surfaces 27 and 28. After the recess 38 has been formed in the head 14 of the blank 11, the header slide 18 and the die 12 are moved apart, thus withdrawing the piercing tip 33 from the head 14 of the blank 11. The latter may be ejected by the rod 16.

Upon the extraction stroke, the piercer tool 17 is unloaded the instant ejection starts. The thimble 26c ties the piercer tool 17 to the anvil 25 but owing to the lost motion provided, the space 26d opens after dead-center and unloads the piercer tool 17 just an instant before extraction begins. Furthermore the work is separated from the piercer tip 33 before the chuck 21 has reached its outermost position in which the parts again become rigidly aligned. In this manner any possibility of damage to the tool or the work during extraction is avoided in case of misalignment.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of my invention, the scope of which is set forth in the annexed claims.

What is claimed is:

1. In a header, a pair of relatively reciprocal members, a tool carried by one of said members having a working portion adapted to engage a work piece supported by the other of said members, and movable means arranged to hold said tool against lateral movement with respect to said one member, one of said elements having associated therewith means operated in

timed relation to the relative reciprocation of said members arranged to move said first named means and release said tool for lateral movement after said working portion has engaged a work piece supported by the other of said members.

2. In a header, a pair of relatively reciprocable members, a tool carried by one of said members having a working portion adapted to engage a work piece supported by the other of said members, and wedge means arranged to hold said tool against lateral movement with respect to said one member, one of said elements having associated therewith means operated in timed relation to the relative reciprocation of said members arranged to move said wedge means and release said tool for lateral movement after said working portion has engaged a work piece supported by the other of said members.

3. In a header, a pair of relatively reciprocable members, one of said members being formed with a recess opening toward the other of said members, a tool positioned in the recess of said one member having a working portion adapted to engage a work piece supported by the other of said members, and movable wedge means holding said tool against lateral movement in said recess, one of said elements having associated therewith means operated in timed relation to the relative reciprocation of said members arranged to move said wedge means to release said tool for lateral movement after said working portion has engaged a work piece supported by the other of said members.

4. In a header, a pair of relatively reciprocable members, one of said members being formed with a recess opening toward the other of said members, a tool positioned in the recess of said one member and having a working portion at its free end adapted to engage a work piece supported by the other of said members, the other end of said tool abutting said one member for the transmission of axial forces through said tool, and movable means holding said tool against lateral movement in said recess, one of said elements having associated therewith means operated in timed relation to the relative reciprocation of said members arranged to move said movable means to release said tool for lateral movement after said working portion has engaged a work piece supported by the other of said members.

5. In a header, a pair of relatively reciprocable members, a tool carried by one of said members having a working portion adapted to engage a work piece supported by the other of said members, wedge means arranged to hold said tool against lateral movement with respect to said one member, one of said elements having associated therewith means operated in timed relation to the relative reciprocation of said members arranged to move said wedge means and release said tool for lateral movement after said working portion has engaged a work piece supported by the other of said members, and means acting to restore said wedge means to lateral movement preventing position after said working portion has moved out of engagement with the work piece.

6. In a header, a pair of relatively reciprocable members, one of said members being formed with a recess opening toward the other of said members, a tool positioned in the recess of said one member having a working portion adapted to engage a work piece supported by the other

of said members, movable wedge means holding said tool against lateral movement in said recess, one of said elements having associated therewith means operated in timed relation to the relative reciprocation of said members arranged to move said wedge means to release said tool for lateral movement after said working portion has engaged a work piece supported by the other of said members, and means acting to restore said wedge means to lateral movement preventing position after said working portion has moved out of engagement with the work piece.

7. In a header, a pair of relatively reciprocable members, one of said members being formed with a recess opening toward the other of said members, a tool positioned in the recess of said one member and having a working portion at its free end adapted to engage a work piece supported by the other of said members, the other end of said tool abutting said one member for the transmission of axial forces through said tool, movable means holding said tool against lateral movement in said recess, one of said elements having associated therewith means operated in timed relation to the relative reciprocation of said members arranged to move said movable means to release said tool for lateral movement after said working portion has engaged a work piece supported by the other of said members, and means acting to restore said movable means to lateral movement preventing position after said working portion has moved out of engagement with the work piece.

8. In combination, a heading tool and a die, said elements being relatively reciprocably mounted, said heading tool having a mounting comprising a frusto-conical socket with an opening of smaller diameter, a chuck within said socket with a frusto-conical outer surface fitting said inner socket surface, and a bore holding said heading tool longitudinally slidably with limited relative longitudinal motion, means for resiliently urging said chuck toward the open end of said socket for initially centering the tool, and means for resisting inward motion of said tool when said die and said tool are brought toward each other with a blank to be worked upon in said die, said chuck overhanging said tool and socket sufficiently for said chuck to be engaged by said die and moved into said socket to permit lateral yielding of the tool when said die and tool are moved toward each other.

9. In combination, a heading tool and a die, said elements being relatively reciprocably mounted, said tool having a mounting comprising a socket tapering to a smaller diameter of an open end, a chuck within said socket having an outer surface adapted to fit said inner socket surface and a bore receiving said tool with relative longitudinal slidable motion between said chuck and said tool, means for resiliently urging said chuck toward the open end of said socket for initially centering the tool, and means for resisting inward motion of said tool when said die and tool are brought toward each other with a blank to be worked upon in said die, said chuck overhanging said tool and socket sufficiently for said chuck to be engaged by said die moved into said socket to permit lateral yielding of the tool when said die and tool are moved toward each other.

10. The method of forming the end of a work-piece by means of a piercing tool or the like which comprises the steps of holding the work-piece against lateral movement, supporting the tool

against lateral movement, causing endwise engagement of the work-piece and the tool, increasing the force acting between the tool and the work-piece to form the latter, and simultaneously relieving the lateral support of the free end of the tool to provide for limited bodily motion of the end of the piercing tool to one side of its neutral axis.

11. In a header, a pair of members carrying cooperating tools, said members being movable axially toward and away from each other, alignment means movably mounted on one of said members, said alignment means in one position engaging and axially aligning the associated tool, said alignment means being movable to another position wherein it frees the associated tool for limited lateral motion, said alignment means including abutment means for engagement with the other of said pair of members to move said alignment means from its tool aligning position to said other position wherein the associated tool is freed for limited lateral motion.

12. In a header, a pair of members carrying cooperating tools, said members being movable axially toward and away from each other, alignment means movably mounted on one of said members, said alignment means in one position engaging and axially aligning the associated tool, said alignment means being movable to another position wherein it frees the associated tool for limited lateral motion, said alignment means including abutment means, means on said header for engagement with said abutment means to move said alignment means from its tool aligning position to said other position wherein the associated tool is freed for limited lateral motion.

13. In a header, a pair of members carrying cooperating tools, said members being movable axially toward and away from each other, a chuck movably mounted on one of said members, said chuck surrounding the associated tool, said chuck having a wedge surface which in one position axially aligns the associated tool, said chuck being axially movable to another position wherein it frees the associated tool for limited lateral motion, said chuck including abutment means for engagement with the other of said pair of members to move said chuck axially from its tool aligning position to said other position wherein the associated tool is freed for limited lateral motion.

14. In combination, tool and die elements, said elements being relatively reciprocably mounted, said tool element having a mounting comprising a tapered socket with an open end of smaller diameter, a punch within and spaced from said socket, a chuck within said socket fitting said tapered socket and having a bore for receiving said punch, said chuck having axially sliding movement relative to said tool and said socket, means for resiliently urging said chuck toward the open end of said socket for initially centering the punch, means for holding said punch against axial motion relative to said mounting when said die and tool elements are brought toward each other with the punch engaging a blank to be worked upon in said die element, and means for engaging said chuck and moving it axially inwardly in its socket and relative to said punch when said die and tool elements are further brought toward each other for deformation of the blank by said punch, thereby freeing said punch for limited lateral motion in said socket.

15. In a header, a pair of members carrying cooperating tools, said members being movable

5 axially toward and away from each other, wedge means carried by one of said members holding the tool carried thereby against lateral movement with respect to its supporting member, one of said tools being arranged to restrain a length of stock against free axial motion and the other of said tools being formed to deform said stock, inter-engaging means between the wedged tool and its associated member to hold the tool against axial motion relative to said member during deformation of said stock, relative motion of said members toward each other to deform said stock causing engagement of said wedge means by the other of said members and axial motion of said wedge means relative to said one member and the associated tool to release the tool restrained by said wedge means for limited lateral movement.

16. In a header, a pair of relatively movable work-holding and work-engaging members, a recess formed in one of said members, a tool positioned in the recess of said one member having a working portion adapted to engage a work piece, movable wedge means in the recess of said one member for holding said tool against lateral movement in the recess of said one member, said wedge means being movable relative to said one member as well as to said tool, resilient means urging said wedge means into position for firm engagement with both said tool and the wall of said recess for preventing lateral movement of said tool in said recess, the other of said members including means for moving said wedge means relative to the wall of said recess and to said tool to release said tool for lateral movement relative to said one member when said members are brought together to deform stock held by said work-holding member.

17. In a header, a pair of relatively movable work-holding and work-engaging members, a recess formed in one of said members, a tool positioned in the recess of said one member with one end projecting therefrom and having a working portion adapted to engage a work piece, the other end of said tool being formed for abutting said work-engaging member for the direct transmission of axial forces from said latter member to the working portion of the tool, movable wedge means carried by said work-engaging member holding said tool against lateral movement in the recess of the latter member, said wedge means being movable relative to said one member as well as to said tool, resilient means urging said wedge means into position for preventing lateral movement of said tool in said recess, said work-holding member including means for moving said wedge means relative to the wall of said recess and to said tool to release said tool for lateral movement relative to said work-engaging member when said members are brought together to deform stock held by said work-holding member.
